UNITED STATES PATENT OFFICE.

EBEN YOUNG, OF NEW YORK, N. Y.

DESIGN FOR A GARMENT.

SPECIFICATION forming part of Design No. 21,564, dated May 24, 1892.

Application filed March 31, 1892. Serial No. 427,281. Term of patent 3½ years.

To all whom it may concern:

Be it known that I, EBEN YOUNG, of New York city, in the county and State of New York, have invented a new and original Design for a Garment, of which the following is a full, clear, and exact specification, reference being had to the accompanying drawings, forming part thereof.

Figure 1 is a front elevation of the jacket and vest, showing my design; and Fig. 2 is a rear elevation of the same, these two figures being deemed necessary to fully illustrate my design.

The leading feature of my design is in the vest, the lower portion of which is arranged to fall below the lower edge of the jacket.

10 is the jacket, and 11 the vest.

As shown in Fig. 1, the front of the jacket is cut away to expose the vest front, and the jacket is shorter than the vest. The vest is 20 buttoned up in front and its lower portion, which, as shown, is scalloped, falls below the bottom of the jacket, and the exposed portions of the vest are provided with surface ornamentation. 25

I claim—

The design for a jacket and vest, herein shown and described.

EBEN YOUNG.
